UNITED STATES PATENT OFFICE.

WILLIAM J. GODWIN, OF BUTLER, PENNSYLVANIA.

PUNCH.

987,355.

Specification of Letters Patent. Patented Mar. 21, 1911.

Application filed August 13, 1910. Serial No. 577,116.

To all whom it may concern:

Be it known that I, WILLIAM J. GODWIN, a citizen of the United States, residing at Butler, in the county of Butler and State 5 of Pennsylvania, have invented certain new and useful Improvements in Punches, of which the following is a specification.

My invention consists of an improvement in punches for jewelers' and others' use, and 10 has for its object to provide a device for punching or swaging metal or forming small centers or holes therein.

The device is intended for use by one hand only, and consists of a hollow stem 15 provided at one end with a suitable punch, preferably removable; at the other with a terminal knob or button; also an impact shoulder or abutment intermediate its ends; a hammer slidingly mounted on the stem 20 and adapted to strike against the abutment, and a tension spring within the hollow stem, as hereinafter more fully described.

Referring to the drawings:—Figure 1 is a view of the device in elevation, in position 25 for use. Fig. 2 is a similar view showing the hammer raised. Fig. 3 is an enlarged vertical section through a portion of the device. Fig. 4 is a perspective view showing one manner of using the tool.

30 The main element of the device is a hollow stem 2 to the lower end of which is secured by screw connection at 3 or otherwise as desired, the terminal bit or punch terminal 4 of any desired form and of wellknown 35 type. At the other end of hollow stem 2 is secured a terminal button or head 5 providing a bearing for the operator's finger, as indicated in Fig. 1, and an annular abutment or bearing 6 is secured to or around 40 the hollow stem 2 at a suitable position between its ends, against which the spring-actuated hammer acts to impart a blow to the punch 4, of the desired force.

45 The hammer consists of a slidingly mounted button 7 having a striking end 8 adapted for movement longitudinally of stem 2 and for the purpose of actuating the hammer, when raised and released, I provide a tension spring 9 within the hollow stem 2. One 50 end of said spring is secured within the lower end of stem 2 as by a rivet or pin 10 engaging the stem and the lower terminal of the spring as shown in Fig. 3, and the other end is engaged by the end of a pin or screw 11 extending through a longitudinal clearance slot 12, of sufficient length to

permit the full stroke of the hammer, if desired.

As shown, the hammer 7 is formed with an annular button-like rounded periphery 60 having under sides sloping downwardly and inwardly toward the hammer striking end 8, whereby the hammer may be readily lifted by the thumb of the operator at any position, and released as indicated in Fig. 1. 65

The operation of the device will be readily understood from the foregoing description. The point of punch 4 is first set against the surface to be punched or swaged, at the proper angle for the blow and held there- 70 against by the finger on button 5. The hammer, which is normally held against abutment 6 by tension of spring 9, is then raised by the thumb more or less according to the blow desired, and released, its impact against 75 abutment 6 driving the point of punch 4 into the metal or other surface operated upon.

The device is particularly adapted to the 80 punching or swaging of small portions of metal as in the setting of stones or gems. Ordinarily many such gems, especially the smaller ones, are temporarily held in position during the operation by the end of the finger, and the metal swaged up around the 85 gem, as in Fig. 4. By my improved instrument this operation is facilitated and the adjustment, manipulation, and operation by one hand is rendered very easy, cer- 90 tain and effective.

The device is very simple and economical 95 in construction, not liable to derangement, and will be found readily adaptable to a variety of uses. It may be made in different sizes or designs and with any strength of spring desired for the purpose intended, or otherwise varied by the skilled mechanic, within the scope of the following claims. 90

What I claim is:—

1. A punch consisting of a hollow stem 100 having a terminal punch and a button head respectively, an external anvil abutment, a slidingly mounted hammer having an annular extension, and an actuating spring within the hollow stem, substantially as set forth. 105

2. A punch consisting of a hollow tubular stem having a tool at one end and a button-shaped holding head at the other, an external anvil abutment, a hammer slidingly mounted on the stem having an annular lifting extension and adapted to strike 110 against said abutment, and a power spring

- within the stem adapted to impart movement to the hammer to thrust it against the abutment when it is drawn backward therefrom and released, substantially as set forth.
- 5 3. In a tool of the class described, the combination of a hollow stem provided with an operating tool, a button-shaped holding head, an external anvil abutment, and a longitudinal slot; of an external slidingly mounted hammer having an annular lifting extension, a tension spring secured at
- 10

one end within the tubular stem, and a pin fixed to the hammer and extending through the slot and secured to the other end of the tension spring, substantially as set forth. 15

In testimony whereof I hereunto affix my signature in the presence of two witnesses.

WILLIAM J. GODWIN.
